UNITED STATES PATENT OFFICE.

CLARENCE ELMER STAUB, OF MASCOUTAH, ILLINOIS.

UNBREAKABLE CLOTHES-PIN.

1,274,344.

Specification of Letters Patent. Patented July 30, 1918.

Application filed February 16, 1918. Serial No. 217,664.

To all whom it may concern:

Be it known that I, CLARENCE ELMER STAUB, a citizen of the United States, residing at Mascoutah, in the county of St. 5 Clair and State of Illinois, have invented new and useful Improvements in Unbreakable Clothes-Pins, of which the following is a specification.

This invention relates to clothes pins and 10 it has for its object to produce a very simple and inexpensive device of this kind which will be practically unbreakable and indestructible by ordinary usage.

A further object of the invention is to 15 produce a clothes pin which may be easily and inexpensively manufactured of sheet metal, which will be serviceable and efficient in use, and the utility of which will not be affected by long continued use.

20 With these and other ends in view which will readily appear as the nature of the invention is better understood, the device consists in the improved construction and novel arrangement and combination of parts 25 which will be hereinafter fully described and particularly pointed out in the claim.

In the drawing:

Figure 1 is a side view illustrating a modification.

30 Fig. 2 is an end view of the same.

Fig. 3 is a sectional view taken on the line 5—5 in Fig. 2.

Corresponding parts in the several figures are denoted by like characters of reference.

The improved clothes pin is produced of an elongated narrow strip of metal by bending the same so as to form an approximately circular head 15 and the limbs 16, said limbs 40 contacting with each other throughout the lengths thereof except at a point about midway of their lengths where each limb is formed with an outwardly bulged portion 17, said bulged portions coöperating to form 45 an elongated eye 18, and at their lower extremities where said limbs are bent outwardly with respect to each other, as seen at 19, to form a throat or inlet portion 20. The metal of which the device is formed should 50 be sufficiently resilient to cause the limbs 16

to be maintained in contacting relation, as above set forth, except when forcibly separated, as will be the case when the device is utilized to secure a garment on a clothes line, said garment and line being inserted 55 through the throat 20 and between the limbs 16 until the elongated eye 18 is reached, the limbs 16 being thus forced apart against the tension of the spring formed by the head portion 15. The garment will thus be firmly 60 secured on the line until the device is removed.

That portion of the strip of metal which is bent to form the head 15 is provided with an exterior longitudinal central channel-like 65 rib 21 that extends almost circumferentially around the head and terminates near the limbs 16. By the formation of such rib the device is materially strengthened and the tension exerted by the spring portion formed 70 by the head 15 will be materially increased, thereby increasing the strength, durability and efficiency of the device.

It will also be noticed that the rib 21 is susceptible of cheap formation incidental 75 to the production of the pin, and that while it does not appreciably increase the cost of the pin it materially prolongs the usefulness thereof, this latter being due to the fact that without the rib 21 the head 15 is likely to 80 be fractured by frequent separation of the limbs.

What is claimed as new is:

The herein described clothes pin, consisting essentially of a narrow elongated strip 85 of resilient metal shaped to form an approximately circular head and a longitudinally extending channel-like rib projecting exteriorly on said head and limbs extending from the head at points opposite the center 90 of the said rib, the inner faces of said limbs contacting with each other except at an intermediate point where outward bulges are formed that coöperate to form an elongated eye, and at their lower extremities where 95 said limbs are bent outward to form a throat or inlet.

In testimony whereof I affix my signature.

CLARENCE ELMER STAUB.
